(57) **ABSTRACT**

It is important to allow a sore or injured muscle to recover after strenuous physical activity or trauma to an affected limb. The device has separate stations that permit all major muscle groups to be massaged or rehabilitated and each station can be operated independently of each other section. The individual sections can be detached from a triangular support member and placed at more ideal locations in the rehabilitation facility, if needed or desired. The device is not intended to replace the expertise of a trained medical provider or personal trainer but is intended to allow a person to self-direct some efforts to massage aching or sore muscles.

MULTI-USE FITNESS AND REHABILITATION MACHINE

PRIOR ART

There are multiple prior art references to exercise devices and devices that rehabilitate sore or injured muscles.

A representative example of this type of device that is specifically designed to rehabilitate back muscles can be found at LaFond, U.S. Pat. No. 6,632,160. In this reference the person is seated and moves an exercise apparatus along a person's back. This device only accomplishes the rehabilitation of one group of muscle areas. Another example that teaches the exercises muscles that support the spine can be found at Carlson, U.S. Pat. No. 7,104,926; this reference primarily focuses attention on the neck muscles.

Other exercise devices such as Hale, U.S. Pat. No. 7,311,644 and Lindquist, U.S. Pat. No. 5,772,614 target different areas of the body but none of the prior art teach a device that can rehabilitate multiple areas of the body in one device.

BRIEF SUMMARY OF THE INVENTION

This device will enable the user to massage different muscle groups, which have been stressed due to either an injury, strenuous physical activity or in need of palliative treatment. It has been determined that rolling out or massaging the muscle accelerates the recovery time for a muscle or group of muscles that have been strained.

One of the difficulties of the prior methods to massage different muscle groups is due to the lack of adequate usable equipment. Typically, a person would roll on a solid hard plastic roller on the gym floor to massage out a back or leg. Not only was this cumbersome it often was distracting to others in the gymnasium or rehabilitation center because of the space that was required.

This device is a machine that will incorporate three separate machines. Each of the machines can be separated and used independently but can also be used as one unit. The use of three machines using one space is to conserve space, but the machines can be detached easily and placed in separate locations, if needed.

The device will consist of three separate stations: a chest and arm station, a leg and arm station and arm and shoulder station. Depending of the particular need of the person the person can either rehabilitate the back by standing on a platform and rotating a roller or solid hard plastic ball across the person's back using a pair of handles that will guide the roller or solid hard plastic ball for that purpose. A chest plate in the front would maintain the person's position and force the person to remain in place as the back of the person is massaged. Another station allows for the legs and arms of a person to be rehabilitated. In this station the person would place his or her leg or arm on a plate and the person would guide a roller over the affected area. The third area would be for the shoulders and arms to be rehabilitated.

A plurality of massage elements, such as a solid hard plastic roller or solid hard plastic ball, will be placed at ideal locations so the person can self-direct the rehabilitation of the muscle using a solid hard plastic roller which will either go over the person's back and shoulders or arm or leg; the solid hard plastic roller may be replaced by a solid hard plastic ball or other device to massage the muscles. In this manner, the individual can self-direct his or her rehabilita-

tion wherein the device will be used for both rehabilitating sore muscles or massaging muscles after sports events.

DETAILED DESCRIPTION OF THE DRAWINGS

- 5 FIG. 1 is an isometric view of the chest and back station
 FIG. 2 is an isometric view of the leg and arm station
 FIG. 3 is an interior view of the leg and arm station
 FIG. 4 is a side view of the leg and arm station depicting
 10 the use of linear bearings
 FIG. 5 is view of the top support structure of the chest and
 back station
 FIG. 6 is a top view of the sections of this device secured
 15 to the triangular support member
 FIG. 7 is an isometric view of the chest and back station
 and the leg and arm station secured to the triangular support
 member
 FIG. 8 is an isometric view of the multiple muscle station

DETAILED DESCRIPTION OF THE EMBODIMENTS

55 This is a 3-in-1 rehabilitation machine with independent parts that will allow an individual to rehabilitate sore muscles; each section can be used independent of every other section that is to be rehabilitated. This device is designed to be self-directed in part by the person, although 60 it can be used in conjunction with a trained physical therapist. This machine is not intended to replace a physical therapist or other trained medical provider.

The device has three separate stations that are attached to a triangular support member 50 and each station can be 65 detached from the triangular support member 50 and used in different locations, if desired. The three stations are designed to rehabilitate specific muscle groups and each of the

sections can be used by the individual separate from each other; the three stations are as follows: a chest and back station **5**, a leg and arm station **3** and a multiple muscle station **6**. Every section can be attached to a triangular support member **50** or can be mounted separately at different locations if desired. On each of the sections is a massage element **7**, which is likely to be either a solid hard plastic roller or a solid hard plastic ball although other massage elements may also be used. Regardless of the type of massage element **7** that is used in the station the selection of the massage element should be firm enough to have the desired effect without injuring the person.

Chest and Back Station

In the chest and back section, the person massages or rehabilitates back muscles from the waist to the neck. This can be used to massage out sore back or shoulder muscles. A pair of stanchions **19** supports the chest and back station; the pair of stanchions **19** are secured to the triangular support member **50** but the chest and back station can be removed from the triangular support member **50** if desired or needed. In use, the person stands on a platform **11** and presses his or her body against a chest plate **15**; the chest plate insures that the person remains in the same place during the activity. The distance of the chest plate can be adjusted to accommodate different sized individuals. The person would then grab a pair of grip handles **23** that will allow the solid hard plastic roller to move across a person's back, either up and down or side to side. A solid hard plastic roller **7** or solid hard plastic ball will press against the person's back and the solid hard plastic roller or solid hard plastic ball will press against the person's back. The grip handles are part of an upper support that will move laterally as well as horizontally or vertically as the person's muscles are massaged.

Support stanchions allows the support structure **13** to move the roller on the chest and back station to move from side to side.

Leg and Arm Station

The second station is a leg and arm station **3**. In the leg and arm station, the person would place his or her leg or arm between the leg and arm roller **25** and a leg and/or arm support plate **27**. The person uses the grip handle **23** and move the solid hard plastic roller over the affected area arm or leg. This leg and arm exercise component would also move up and down and side to side depending on the particular body shape and size of the individual being affected. The person can rehabilitate or massage an arm muscle or a leg muscle by draping the arm or leg between the leg and support plate **27** and the roller **25**. The plate may also tilt to accommodate the flexibility of a person.

In the leg and arm station the solid hard plastic roller is hinged to further accommodate the surface of the person to prevent further injury as the solid hard plastic roller is pressed against the limb of the person. A tension knob **33**, which is attached to a gas spring **35**, allows the person or trained medical provider or personal trainer to adjust the tension of the solid hard plastic roller as it impacts the person's limb. Either the arm, from wrist to shoulder or leg from ankle to upper thigh can be massaged at this station.

Multiple Muscle Group Station

The third station **6** is used to rehabilitate multiple muscles or groups of muscles. The third station can be rotated on the triangular element to position the appropriate massage element **55**, **60**, **65** in place to address the specific area of concern. For instance, if the shoulder area needs to be rehabilitated, this station can be rotated and locked in place so

that the appropriate massage element **60** can be locked in place at the correct height for that individual. Once in position the person can then place the massage element **60** on the affected muscle group to rehabilitate the muscle group. The other massage elements **55**, **65** on the shoulder and arm station are used to rehabilitate a person's forearm muscles or leg muscles for instance by rolling the affected muscle group over the appropriate solid hard plastic roller. Like the other sections this section can be detached from the triangular element and used independently of each of the other stations. The height of the third station can be adjusted according to the needs of the user. On that same station the station can be rotated to position the massage element in the appropriate position to massage the arm or leg for example.

The invention claimed is:

1. A multi-use fitness and rehabilitation machine that is comprised of a triangular support member;

a chest and back station;

wherein the chest and back station can be attached to the

triangular support member;

wherein a chest plate is provided;

wherein an upper support is provided;

wherein a pair of grip handles are provided;

said grip handles are connected to the upper support;

wherein the upper support moves from side to side;

wherein the upper support moves up and down;

wherein a platform is provided on the chest and back

station;

wherein a massage element is provided in the chest and back station;

wherein the massage element moves as the person moves the grip handles;

a leg and arm station;

wherein a plate is provided;

said plate is tilttable;

said plate can be locked in place;

a multiple muscle station;

wherein the multiple muscle station is rotatable;

wherein the height of the multiple muscle station is adjustable;

wherein the multiple muscle station can be locked in place;

said multiple muscle station can be locked in place on the triangular support element;

wherein a plurality of massage elements are provided.

2. The multi-use fitness and rehabilitation machine as described in claim 1 wherein the massage element is a solid hard plastic roller.

3. The multi-use fitness and rehabilitation machine as described in claim 1 wherein the massage element is a solid hard plastic ball.

4. The multi-use fitness and rehabilitation machine as described in claim 1 wherein the chest and back station can be removed from the triangular support member.

5. The multi-use fitness and rehabilitation machine as described in claim 1 wherein the leg and arm station can be removed from the triangular support member.

6. The multi-use fitness and rehabilitation machine as described in claim 1 wherein the multiple muscle station can be removed from the triangular support member.

7. The multi-use fitness and rehabilitation machine as described in claim 1 wherein the tension of the roller in the leg and arm station can be adjusted.
